UNITED STATES PATENT OFFICE.

FRANK M. ZIMMERMAN, OF AURORA, ILLINOIS.

SWITCH FOR TROLLEY-WIRES.

No. 869,955.

Specification of Letters Patent.

Patented Nov. 5, 1907.

Application filed October 23, 1905. Serial No. 283,897.

To all whom it may concern:

Be it known that I, FRANK M. ZIMMERMAN, a citizen of the United States, residing in Aurora, Kane county, Illinois, have invented certain new and useful Improvements in Switches for Trolley-Wires, of which the following is a full and correct description of the same, reference being had to the accompanying two sheets of drawings, forming a part hereof, and in which

Figure 1 shows my said device in top plan view; Fig. 2 shows the same in sectional side elevation, taken on the cutting plane 2 2 of Fig. 1; Fig. 3 shows Fig. 1 in bottom plan view with both switch-blades in their normal position; Fig. 4 shows Fig. 3 with its switch-blades receiving a trolley-wheel at the switch-point; Fig. 5 shows a cross-section of Fig. 1 on the cutting-plane 5 5 of Fig. 1; Fig. 6 shows a cross-section of Fig. 1 on the cutting-plane 6 6 of Fig. 1; Fig. 7 shows a cross-section of Fig. 4 on the cutting-plane 7 7; Fig. 8 shows a switch-blade in front view, or as seen from the front or point of 20 the switch; Fig. 9 shows a rear view, or as seen from the butt-end of the switch.

Like reference letters denote like parts throughout.

As heretofore constructed trolley-switches could not pass a trolley-wheel without manual assistance in one way if it was to pass in both directions. In my device said manual assistance is dispensed with and the trolley-wheel passes over the switch from either direction with equal facility.

The object of my invention is to provide a trolley-wire switch which shall act automatically and place itself rightly for the trolley-wheel in whichever way the said wheel may be approaching it. To attain said desirable ends I construct my said new device in substantially the following manner; namely;

I provide a flanged and ribbed body, cap, or cover *a* having flanges *a'* and provided with special cells, or chambers *b* near the point-end of the switch in which to hang the switch-blades, together with suitable cells *c* (Fig. 2) near the rear end of the switch to receive and 35 hold the pins or lugs *c'* which carry the rear end of the switch-blade.

Depending from the front end of the switch is a web *d* to which is attached the single wire-holding clasp *e* holding the trolley-wire *f* and said clasp is secured to 45 the web *d* by means of a screw *d'* (Fig. 2) and said wire *f* is raised, quite sharply, from the inner end of the clasp *e* and is clamped against the roof of the cap by means of a split bolt *g* the legs of which stride said wire *f* and the rib *h* and on the rib *h* rides a washer *i* and on it is a nut *i'* 50 on the bolt. Beyond the bolts *g* the rib *h* consists of two parts *h'*.

From the rear end of the switch run wires *f* and *f'* of which the latter terminates beyond the bolt *g* and is held thereby, as shown, and each of said wires is provided with a clasp *e* which is fastened to a dependent

rib *h* and fastened to one of said ribs with a screw *d'* (Fig. 7), and two split bolts *g* hold the wires *f* and *f'* to the cap-roof from which said wires descend to the front end of the rear wire-clasps *e*. Between the inner ends of said three wire-clasps *e*, vibrate, laterally, two 60 switch-blades *j* which at their forward ends have high lugs *l* and which pass to the top of the raised cell *b* where they are hung on pins *k*, and near their rear ends said blades *j* are provided with pins *c'* which are parallel to the lower or trolley edges of the blades and 65 are at the top edge of the rear ends of the blades *j*, and said pins *c'* and *k* are so placed as to cause the blades *j* to take their normal positions, relative to the other co-working parts as shown in Fig. 3, their rear ends are about half the thickness of the blade wider out, on each 70 side, than the space over the butts of the clasps *e*, and in the front the points of the blades *j* stand away far enough from the wire *f* to readily pass outside of the approaching trolley-wheel, as clearly indicated in Fig. 4, the edges *j'* being rounded outwardly to insure said 75 result, the trolley-wheel always coming at an angle to the line in the direction of the switch to be taken, thus, thereby, slipping inside of one of the round faces *j'* and thus pushing its switch-blade outward, while, at the same time, the position of the trolley-wheel 80 reaches over and catches the opposite switch-blade within the outer edge of its groove and, thereby, throws the point of the blade *j* against the side of the wire *f* before the tread of the wheel *m* is fairly on the wheel-edge of the blade *j*, and which, as it advances, also 85 throws the rear end of the blade against the side of the wire and thus passes the trolley-wheel smoothly and easily onto the wire-clasp *e* and from it the wheel runs smoothly onto its wire, after which the switch-blades assume their normal positions by gravity. When the 90 trolley-wheel runs in the opposite direction to the one shown the grooved tread readily catches the heel of the switch-blade and throws it against its wire and at the same time brings the point-end of the switch-blade against its wire so that the wheel *m* may run 95 easily from one clasp *e* to the other. The opposite switch-blade will then always be pushed out and away to its outer position, or farthest from the trolley-wire. Studs *n* under the pins *k* on the blade *j* strike against the cap-sides and prevent said blades from passing 100 outward beyond their normal position and also aid in bringing the blade within the reach of the groove of the trolley-wheel.

My construction of switches passes a trolley-wheel from one wire to the other with scarcely a break in the 105 smoothness and evenness of the line on which the wheel-tread rolls, and the switch is equally effective for wheels passing in either direction. The parts are housed and, thereby, undisturbed by ice or sleet. The trolley-pole *o* always sets its wheel at the angle through 110

which, with my mechanism, my said results are attained.

What I claim is:

1. The combination with a main and divergent trolley-wires and switch-blades suspended and movable, laterally, from end to end and in same direction at their lower edges, of a trolley-wheel to close one of said blades to the main wire in going in either direction to said switch. 25
2. The combination with a main and divergent trolley-wires and switch-blades suspended and movable, laterally, from end to end and in same direction at their lower edges, of a trolley-wheel to converge one of said blades to said main wire and to, simultaneously, diverge the opposite one of said blades from said main wire while going in either direction to said switch. 30
3. The combination with a main and divergent trolley-wires, of switch-blades on fixed points, said blades normally apart and of largest motion at their point-ends, and vibratable transversely to their vertical plane of direction 35
4. The combination with a main and divergent trolley-wires, of switch-blades on fixed suspensions, and vibratable therefrom, transversely to their vertical plane of direction, 40

of largest motion at their point-ends, each, alternately, touching the side of the main wire.

5. The combination with a cap, main and divergent wires thereto, switch-blades, suspended from said cap and movable, laterally, from end to end and in same direction at their lower edges, of a trolley-wheel to close one of said blades to the main wire in going in either direction to said switch. 30

6. The combination with a main and divergent trolley-wires, of switch-blades to said several wires, on fixed suspensions, normally apart, and of largest motion at their point ends, vibratable towards each other, and automatic means to connect either blade with the main and a divergent trolley-wire. 35

7. The combination with a main and divergent trolley-wires, and switch-blades, normally open, of a trolley-wheel with but a single flange on each side thereof to close one of said blades with one of its flanges, in going in either direction to said switches. 40
